METHOD AND APPARATUS FOR HEATING
OILS

Clive M. Alexander, Louisville, Ky.

Application March 26, 1937, Serial No. 133,208

3 Claims. (Cl. 196—116)

This invention relates to improvements in tubular heaters or furnaces of the type utilized in various industrial processes for the heating of fluids to desired temperatures while such fluids are undergoing passage through elongated zones of restricted cross-sectional area. While tubular heaters of this character are employed in many industrial capacities, they are now quite widely used in the heating of hydrocarbon oils in processes wherein such oils are subjected to heating for effecting the distillation or molecular decomposition thereof, the present invention providing an improved tubular heater especially adaptable for the efficient heating of such oils to desired processing temperatures.

Tube stills or converters, as ordinarily constructed for the continuous heating of moving streams of hydrocarbon oils in the liquid, vapor or mixed phases, involve a suitable wall structure forming a heat-confining enclosure in which is situated a vertical bridge wall so disposed as to divide the enclosure internally into a combustion or radiant heat chamber, in which combustion is actively maintained by the operation of fuel burners or the like, and a spaced convection chamber, the latter receiving heat by the passage of furnace gases from the combustion chamber passing over the top of the bridge wall, the furnace gases being discharged from the bottom of the convection chamber by way of a flue leading to the outlet stack or chimney of the heater. In such heaters, it is a common expedient to arrange the oil heating tubes in both the combustion and convection chambers, depending upon the quantity of heat input which it is desired to impart to each particular bank of tubes through which the oil or vapors thereof are passed. Thus in a single furnace of the type set forth, it is common to carry out simultaneously several different processing operations, such as the heating of oils to high temperatures wherein rapid molecular decomposition of high boiling oils into lower boiling oils takes place, the heating of heavy oils to incipient conversion temperatures to obtain control of viscosity ranges, to heat oils to distillation temperatures without molecular change, and other possible operations, such as reforming low-boiling oils composed mainly of paraffin hydrocarbons into low boiling oils composed mainly of unsaturated hydrocarbons, or the polymerization of normally gaseous hydrocarbons into liquid hydrocarbons.

Such a furnace or converter may be designed to carry out two or more of these operations wherein different processing temperatures are

demanded by placing the tube banks in different locations within the furnace with respect to the heat generating burners. Thus those operations requiring high temperatures, such as in cracking or reforming, are placed in the furnace so as to be located in the zone of higher temperature therein, and those requiring lower temperatures, such as viscosity breaking or simple distillation, in zones of lower furnace temperature.

This usual arrangement of heating tubes, however, does not provide for any particular flexibility in the control of the heat input into any one of the heat absorbing sections or tube banks of the furnace independently of and with respect to the remaining sections or tube banks, and it is one of the important objects of the present invention to provide an oil heating furnace of the multiple tube bank type wherein through improved control of the movement of the furnace gases, better regulation of the heat input into one or more selected tube banks is readily obtainable.

Another object of the invention resides in the provision of a tubular heater of the character set forth wherein the heater walls are so arranged as to provide a combustion zone and a pair of relatively spaced convection passages containing banks of oil heating tubes, one of said passages having its lower portion in communication with a stack outlet or chimney while the other of said passages has its lower end communicating by means of a conduit with the lower portion of the combustion zone, there being a furnace gas recirculating means arranged within said conduit, whereby, through the employment of this construction, independent thermal conditions can be established within said passages without varying the setting of the combustion creating devices disposed in the combustion zone to the end of obtaining the desired transfer of heat from the furnace gases to the oils passing through the heating tubes but without injury to the tubes or overheating or underheating of the oils passing therethrough.

I obtain such improved control of heat input into the various sections or banks of the fluid heating tubes primarily through the employment of an improved means for effecting forced recirculation of the furnace gases within the heater at variable and controllable rates of flow so that certain sections or banks of the heating tubes receive their normal heat in a conventional manner from the operation of the fuel burners and the furnace gases resulting therefrom, while another independent section or tube bank receives its heat by the forced recirculation of the

furnace gases at desired rates of flow through the furnace.

I am aware that heaters or furnaces for oil heating operations have been used involving a combustion zone, a convection zone, an outlet stack, and means for returning the furnace gases to the combustion zone following passage thereof through the convection zone. My present invention, however, is distinguished from such earlier heaters by the inclusion therein of an additional and separate convection zone (or zones) having forced circulation of hot furnace gases therethrough, which gases are withdrawn from the combustion zone by the operation of a variable speed hot gas recirculation fan, or the equivalent thereof, and returned to the combustion zone, whereby to regulate with variable control the rate of heat input into the heat absorbing structures within said additional convection zone while a substantially fixed rate of fuel combustion is taking place in the combustion zone.

For a further understanding of the invention, reference is to be had to the following description and the accompanying drawings, wherein:

25 Fig. 1 is a vertical sectional view taken through a tubular heater constructed in accordance with the present invention, and illustrating conventional oil fractionating apparatus which may be used in connection therewith.

30 Fig. 2 is a similar view showing a slightly modified form of the invention, wherein a steam jet is employed as the motivating means for effecting recirculation of furnace gases.

35 Fig. 3 is a similar view through a further modified form of heater wherein but a single convection passage is used for the oil heating tubes.

40 Fig. 4 is a variation of a form of the invention disclosed in Fig. 3 showing the use of a steam jet for recirculating the furnace gases and a slightly different arrangement of the oil heating tubes.

Fig. 5 is a further modified form of a tubular heater utilizing the features of the present invention.

45 Referring more particularly to Fig. 1 of the drawings, the numeral 1 designates a tubular heater or converter which has been especially designed for use in oil conversion systems. In the form of the invention illustrated in Fig. 1, the tubular heater comprises side, end and roof walls 2, 3 and 4, respectively, of suitable refractory materials and embodying customary features for effecting the thermal insulation thereof, the said walls defining an enclosing structure. Also arranged within the converter are spaced vertical bridge walls 5. These walls define between them a combustion zone 6, in which may be arranged combustion developing means such as oil or gas burners, as indicated at 7. The bridge walls 5 are spaced from the end walls 3 to produce convection passages 8 and 9 through which the furnace gases, developed within the zone 6, pass downwardly after first having passed over the upper edges of the bridge walls 5.

60 The lower portion of the passage 8 communicates by way of an underground duct or conduit 10 with the lower portion of the combustion zone 6, in order that the furnace gases obtained from the passage 8 may be recirculated through the heater to provide improved features of temperature control, as will be hereinafter explained. Preferably, the duct 10 is provided with means for effecting the positive and forced advance of the furnace gases therethrough from the convection passage 8 to the combustion zone.

75 Such a means may take a variety of forms but I

prefer to employ a flexible unit such as a rotary fan 11 driven by a variable speed motor so that the R. P. M. of the fan rotor will be subjected to considerable variation. Similar results may be obtained, as shown in Fig. 2, with the use of a steam jet or injector 12 arranged within said duct or conduit and so positioned as to effect travel of furnace gases through said duct or conduit for re-delivery to the combustion zone. Variation in the operation of the steam jet or injector 12 may be obtained by regulation of the amount of steam, or other motivating fluid delivered thereto.

The lower portion of the convection passage 9 communicates at its lower end, in the form of 15 my invention illustrated in Figs. 1 and 2, with a compartment 13 arranged in the foundation 14 of the heater. Arising from the foundation 14 immediately over the compartment 13 is a furnace gas outlet stack or chimney 15, provided 20 with a suitable damper 16. The furnace gases, after passing through the passage 9, are not recirculated to the combustion zone but are delivered to the stack 15 at a low temperature for discharge to the atmosphere. 25

Arranged within the passage 9 is a bank of primary oil heating tubes 17 and oil to be heated in these tubes enters the lower portion of the same by way of the pipe line 18, which may extend from any suitable source of supply. The 30 oil is forced upwardly through the tube bank 17, in counter-current relation to the downward flow of the furnace gases through the passage 9, with the result that the stack gases, when delivered to the compartment 13, possess a low temperature in order to obtain maximum heat 35 economy.

Oils leaving the top of the bank of tubes 17 pass by way of a connection 19 through a bank of roof tubes 20, arranged within the converter 40 adjacent to the roof 4. These tubes are heated mainly by radiant heat derived from the operation of the burners 7. From the tubes 20, the hydrocarbons undergoing heat treatment are passed to a third bank of tubes 21 situated in 45 the passage 8, the oil passing through this last-named bank of tubes generally in concurrent flow with the passage of the furnace gases therethrough.

During the passage of the hydrocarbons 50 through the tubes 21, conversion or reaction temperatures are maintained or slightly increased, providing for the necessary time factor in obtaining a desired rate of conversion of, for instance, higher boiling hydrocarbons to lower 55 boiling hydrocarbons. The heat input imparted to the hydrocarbons passing through the tubes 21 is susceptible to variation, without altering the setting or rate of combustion produced by the operation of the burner 7, by varying the speed 60 of operation of the hot gas fan 11. With the use of this fan, or its equivalent, desired and accurate control of the temperatures of the hydrocarbons leaving the tubes 21 may be readily obtained.

65 In association with the converter, the hydrocarbons discharged from the tubes 21 pass through a pressure reducing valve 22 and may enter a flash chamber, or enlarged separating zone, of the type indicated at 23. In this chamber, heavy oils which are not vaporized under the temperatures and reduced pressures existing in the flash chamber, drop to the bottom of said chamber and are withdrawn from the system as fuel oil. The lighter or vaporous hydrocarbons 70

pass overhead from the chamber 23 and are delivered to a fractionating column 24. The liquid condensate or distillate which collects in the bottom of the fractionating column may be returned to the converter as recycle stock for re-heating, while the vapors which pass overhead from the fractionating column may be condensed as at 25 and thence delivered to a gas separator 26 containing a pressure reducing valve 27 in the top thereof, through which the fixed gas generated by the system is discharged, the liquid condensate being withdrawn from the bottom of the gas separator as a motor fuel spirit.

Another variation of the present invention has been disclosed in Fig. 2, wherein hydrocarbon oils or other fluids to be heat treated enter the converter at 30 and pass through the roof tubes 20a and are thence transferred to the bank of tubes 17a in the passage 8, leaving the converter by way of the pipe line 31. An independent bank of tubes 21a is disposed in the passage 8. The heat treated products leaving the tubes 17a and 21a may be delivered to a common point of discharge, such as the flash chamber 23. As shown in Fig. 2, positive advance of the furnace gases through the duct or conduit 10 may be effected by the employment of the steam jet or injector 12, in lieu of the fan 11.

In the form of the invention depicted in Fig. 3, the converter comprises but a single convection passage 9b and a single bridge wall 5b. The lower end of the passage 9b communicates with the stack compartment 13b and also with a duct or conduit 10b leading to the combustion zone 6b, the said duct or conduit having positioned therein a variable speed hot gas fan 11b. Control dampers 32 and 33 are arranged in the lower portion of the passage 9b to provide for the deflection of hot gases as desired either into the compartment 13b and thence to the outlet stack or to the duct or conduit 10b and thence back to the combustion zone. If desired, the passage 9b may be provided with separate banks 34 and 35 of oil heating tubes, the upper bank being connected with the roof tubes 20b by way of the connection 36.

In Fig. 4, a similar construction is used, with the exception that the lower portion of the bridge wall 5c is provided with an opening 37 establishing communication between the convection passage 9c and the lower portion of the combustion zone 6c. In the opening 37, there is arranged a steam jet or injector 12c.

In Fig. 4, a single bank of tubes 38 has been shown, which bank is independent of the radiant heat tubes 39 and 40 positioned, respectively, adjacent to one of the vertical walls of the combustion zone and the roof wall 4c thereof.

In view of the foregoing, it will be seen that in tubular heaters of the type illustrated in Figs. 1 and 2, the use of a hot gas fan or steam jet for furnace gas recirculation permits the heat input applied to the coil of one convection passage to be independently varied with respect to that applied to the heating coil in the other convection passage. Changes in firing will vary the heat input in the coil disposed in the convection passage leading to the stack or chimney, whereas changes in the rate of gas recirculation will vary the heat input in the coil disposed in the convection passage which communicates at its lower end with the combustion chamber of the converter. This improvement in heater operation has a number of advantages: A single combustion zone may be used to supply heat to

two separate coils with independent control of heat input for each coil and, in addition, controlled convection heat input can be obtained either from mild heating of heavy oils subject to coke formation, or for very high temperature heating of refractory oils without undue tube stress and failures.

With the arrangement of the tubes disclosed in Fig. 2, the tube bank arranged in the passage 8 may be used for the heating of oils to incipient cracking temperatures providing for viscosity control, while the tube banks disposed in the roof of the furnace and in the convection passage 9 may be used to effect molecular decomposition of the oils. The tube arrangement disclosed in Fig. 1 is particularly applicable to the molecular decomposition of oils or to reforming or polymerization operations since after the oil has been brought to desired reaction temperatures, the time period and control of the final exiting temperatures may be conveniently regulated by controlling the recirculation of furnace gases through the passage 8. Regardless, however, of the particular operations which may be carried out in the furnace, the present invention provides for flexibility in the control of heat input into one or more of the coils of a multiple coil furnace.

In Fig. 5, a heater has been disclosed involving heat confining walls so disposed as to produce a combustion chamber 6d, a bridge wall 5d and a convection chamber 8d, the latter being in communication with the combustion chamber at the top thereof. Within the chamber 8d, there is disposed a bank of oil heating tubes 21d and heat is applied to said tubes by the forced passage of the furnace gases downwardly through the chamber 8d. The bottom of this chamber communicates with a conduit 10d in which is located a variable speed gas recirculating fan or blower 11d, by which the furnace gases, after passing through the chamber 8d, are returned to the combustion chamber for recirculation through the heater.

Located above the chamber 8d and in substantially vertical registration therewith is a second convection chamber 9a in which is located a bank of oil heating tubes 17d, the latter being connected by a pipe line 19d with a bank of radiant heat tubes 20d located contiguous to the walls of the combustion chamber 6d. A portion of the furnace gases discharged from the combustion chamber 6d passes upwardly under normal draft flow through the chamber 9a and finds exit as at 13d to an outlet stack 15d.

With the construction disclosed in Fig. 5, it will be observed that the tubes 20d in the combustion chamber are mainly heated by radiant heat, and the rate of heat input thereto is only controllable by variations in the operation of the burner or burners 1d. The coil 11d receives mainly convected heat derived from the furnace gases passing upwardly under normal draft flow through the chamber 9a, and variations of heat input into this coil are likewise subject to the setting of the burner or burners 1d. The independent convection coil 21d may have the rate of heat input thereto varied without disturbing the setting of the burner 1d by variations in the speed of operation of the fan 11d, thus providing for independent control of the heating of this particular tube bank.

It will thus be seen that the present invention provides: first, an improved form of tubular heater construction having an independent con-

vection zone with forced hot furnace gas circulation. Second, a construction of heater with two tubular coils or heating sections therein so located that one of such coils or sections receives its heat input in the greater proportion from radiancy and the other in the greater proportion from convection with means for independently varying their heat inputs. Third, the invention provides a method of controlling independently the heat input to or temperature rise of liquids flowing within multiple coils in a tubular heater of the type described, the method further providing for independently controlling the heat input to or temperature rise of liquids flowing within separate sections of a continuous coil in such a heater, or separately controlling the heat input to two coils located in a furnace having one combustion zone. Moreover, a method is provided for dispersing the heat of combustion from a single combustion zone in controlled and variable proportions to two heating coils obtaining their heat from the single combustion zone.

It will be understood that the essential features of the invention may be carried out with the use of apparatus other than that disclosed in the several figures of the drawings, and, therefore, my invention is subject to such further variations or modifications, apparent to those skilled in the art, and which may be said to fall fairly within the scope of the following claims.

What is claimed is:

1. The method of heating a plurality of streams of hydrocarbon oils of varying boiling ranges which comprises effecting fuel combustion within a single confined combustion zone, diverting the resulting furnace gases to form two independent streams, passing said streams through a pair of convection zones, passing one of said streams following travel thereof through one of said convection zones to the atmosphere, returning the furnace gas stream passed through the other of said convection zones to the combustion zone, controlling the rate of flow of the furnace gas stream passing through said last-

named convection zone, and passing hydrocarbon oils of different boiling ranges through heat absorbing devices arranged in said convection zones.

2. A heater comprising a wall structure provided internally with a pair of spaced bridge walls of refractory heat transmission resisting materials, said walls dividing the heater internally into a centrally disposed combustion chamber and a pair of spaced convection chambers, one of the latter being arranged at each side of the combustion chamber, heat absorbing fluid heating means arranged within each of said convection chambers, an outlet stack in communication with the lower end of one of said convection chambers, a duct uniting the lower end of the other of said convection chambers with said combustion chamber, and means for effecting a forced flow of furnace gases withdrawn from said last-named convection chamber through said duct and into said combustion chamber at variable and controlled rates of flow.

3. The method of simultaneously heating a plurality of hydrocarbon fluids of different molecular weights, the improvement which comprises effecting fuel combustion within a confined combustion zone, diverting the furnace gases resulting from such combustion into two separate streams, passing said streams through a pair of spaced convection zones wherein each of said zones contains heat absorbing structures through which hydrocarbon fluids of different molecular weights are passed, discharging one of the furnace gas streams following passage thereof over the heat absorbing structure in the zone through which the gas stream is passed to the atmosphere, returning the other of said furnace gas streams following passage thereof over the heat absorbing structure in the convection zone through which it travels to said combustion zone, and controlling the rate of flow of the last-named furnace gas stream through its convection zone to regulate the absorption of heat by the structure in said last-named zone.

CLIVE M. ALEXANDER. 45
